UNITED STATES PATENT OFFICE.

ROBERT J. McLANAHAN, OF WOODLAWN, PENNSYLVANIA.

WATER-CLOSET.

Application filed March 20, 1924. Serial No. 700,546.

To all whom it may concern:

Be it known that I, ROBERT J. McLANAHAN, residing at Woodlawn, in the county of Beaver and State of Pennsylvania, a citizen 5 of the United States, have invented or discovered certain new and useful Improvements in Water-Closets, of which improvements the following is a specification.

My invention relates to improvements in 10 the structure of water closets. It is illustrated in the accompanying drawings, in which Fig. I is a view in medial and vertical section of the entire installation; Fig. II is a view in horizontal section on the plane indicated by the dotted line II—II, Fig. I, of 15 the same structure; and Fig. III is a view in section on an irregular surface indicated by the dotted line III—III, Fig. I, illustrating the arrangement of the passage- 20 ways.

The water closet installation includes the familiar bowl 1, flushing tank 2, and flushing pipe 3. Flushing is effected in the usual manner by unseating a valve 4, ordinarily 25 in the form of a rubber ball, which controls passage from tank 2 to pipe 3. The flushing pipe opens into a space within the water closet fixture itself, from which space there is connection to a nozzle 5 (which spouts a 30 stream into the ascending arm 6 of the siphon discharge pipe) and from which space streams flow down the sides of the bowl 1. This space in the ordinary construction and arrangement is, when the water closet is in- 35 active, freely open to the air. The flushing pipe 3, therefore, is at such times empty, and the lower face of the valve 4 is exposed to atmospheric pressure. The effective force tending to hold the valve 4 to its seat is 40 therefore merely the weight of the water above it. There is apt to be leakage, and this leakage is apt to go on, with a waste of large quantities of water in the long run.

My invention consists in a particular construction within the water closet fixture itself, whereby at no time is the lower face 45 of the valve 4 freely exposed to the atmosphere, but at all times of inaction the flushing pipe is full of water. At such times the weight of the water in the flushing pipe tends to create a vacuum beneath the valve, and tends therefore to hold the valve more firmly to its seat. The consequence is that 50 leakage is prevented: an escape of water,

which in the long run may amount to great 55 quantities, is guarded against.

To this end, the space within the fixture and disposed above the discharge pipe 6 and rearward of the bowl is divided by a partition 7, the particular arrangement of which 60 will be understood on comparing Figs. II and III. Its effect is to provide a closed conduit 8 continuous with the flushing pipe 3 and leading to a point below the level of water standing in bowl 1 (indicated at a) 65 and at or below the level of the nozzle 5. At the lowest point, the web 9 which as usual is spread between the parallel reaches of the siphon discharge pipe is penetrated by an orifice 10, and a continuation 11 of the 70 conduit ascends thence to the space 12 above, and on the opposite side of the partition 7. From this space 12 the flushing stream has access to the orifices 13 through which the water emerges to wash the sides of the 75 bowl. To this space 12 also the overflow pipe 14 from tank 2 may conveniently be made to discharge.

The action is the familiar one. Water stands in the fixture normally at a level indicated by the dotted line a, the level determined by the high point in the siphon discharge pipe 6. When the closet is to be flushed, valve 4 is manually raised from its seat, the body of water from the tank 2 descends through the flushing pipe 3 and through the passageway 8 to the low point, and part of the flushing stream is there projected through the nozzle 5 to set in motion the evacuating stream through the suction discharge pipe 6. The remainder of the flushing stream passing through the orifice 10, and ascending through the passageway 11, and thence to the space 12, emerges 80 through the orifices 13 and washes the walls 85 of the bowl. Evacuation continues until 90 in consequence of the failure of the stream, the suction action is ended and the remaining supply of water comes to rest within the bowl at the level a.

After a flushing operation and as the tank 2 fills again, the valve 4 will be brought to its seat by the escape of water through the relatively contracted nozzle 5, and thereafter the pressure of the accumulating 105 weight above it will assist in holding it to its seat. At the same time, the water which fills both the flushing pipe 3 and the pas-

sageway 8 will be retained; there will be no escape of water through the nozzle, but the weight of the retained column of water tending to escape, will the more firmly hold 5 the valve 4 by suction to its seat.

I claim as my invention:

1. In a water-closet structure the combination of a bowl, a siphon discharge passageway leading from the bowl, an upwardly directed nozzle opening into the ascending arm of the siphon passageway, a flushing tank, a conduit for the flushing stream with continuous and unported walls leading from the flushing tank downward 10 to the level of the said nozzle, and from this point ascending to an orifice at the upper rim of the bowl, and an overflow pipe leading from the tank and discharging into said conduit in the region of its ascent to the orifice at the upper rim of the bowl, substantially as described.
2. In a water-closet structure the combination of a bowl, a siphon discharge passageway leading from the bowl and centered in the vertical mid-plane through the bowl, an upwardly directed nozzle opening 15 into and ascending arm of said siphon pas-

sageway, a flushing tank, a casing enclosing the siphon discharge passageway on either side, a vertically extending septum formed integrally with the siphon discharge passageway and dividing the space within the said casing into descending and ascending conduits, said septum, elsewhere imperforate, being perforated below the high point in the siphon passageway by an opening through which such conduits are brought into communication one with the other, the aforesaid nozzle opening from the line of flow through such descending and ascending conduits at a point adjacent the opening through said septum, communication from the casing at the upper end of the ascending conduit to the rim of the bowl, and an overflow pipe leading from the flushing tank and opening to said casing at the upper end of the ascending conduit formed therein as aforesaid.

In testimony whereof I have hereunto set my hand:

ROBERT J. McLANAHAN.
